United States Patent

Des. 237,843
Patented Dec. 2, 1975

237,843

FACE GUARD

Hugh T. Peterson, 1906 Kohl St. 19115, and Thomas M. Fallon, 4642 Kendrick St. 19136, both of Philadelphia, Pa.

Filed Apr. 22, 1974, Ser. No. 462,830

Term of patent 14 years

Int. Cl. D2—03

U.S. Cl. D2—233

FIG. 1 is a front perspective view of a face guard showing our new design;

FIG. 2 is a front elevation view thereof;

FIG. 3 is a rear elevation view;

FIG. 4 is a top plan view;

FIG. 5 is a bottom plan view;

FIG. 6 is a left side elevation view;

FIG. 7 is a right side elevation view; and

FIG. 8 is a section view thereof taken along the line 8—8 in FIG. 1.

We claim:

The ornamental design for a face guard, substantially as shown and described.
